UNITED STATES PATENT OFFICE.

MOSE FISHER, OF PLAIN, NEW MEXICO.

REVOLVING FOLDING TABLE.

Application filed February 28, 1922. Serial No. 539,870.

To all whom it may concern:

Be it known that MOSE FISHER, a citizen of the United States of America, residing at Plain, in the county of Quay and 5 State of New Mexico, has invented new and useful Improvements in Revolving Folding Tables, of which the following is a specification.

The object of the invention is to provide 10 a construction of revolving or serving table which may be readily folded for shipment under such conditions as to protect the normally exposed and highly finished portions from contact with adjacent objects to avoid 15 mutilation or scratching, and at the same time to provide a device which when set up is of strong and substantial form; and with these objects in view the invention consists in a construction and combination of parts 20 of which a preferred embodiment is shown in the accompanying drawings, wherein:—

Figure 1 is a side view, and

Figure 2 is a plan view of a table constructed in accordance with the invention.

25 Figure 3 is an inverted plan view of the main table.

Figure 4 is a central sectional view of the same taken in a plane transverse to that of the joint between the leaves or members of 30 the table top.

Figure 5 is a section taken at right angles to the plane of Figure 4.

Figure 6 is an inverted plan view of the serving table.

35 Figure 7 is a sectional view of the serving table when folded.

Figure 8 is a sectional view, and

Figure 9 is a side view of the main table with the parts in the folded position.

40 The main table top consists of leaves or members 10 and 11 which are connected at their adjacent diametrical edges at the center by a hinge 12 arranged to permit of the folding of the sections so as to bring the

45 upper finished surface thereof into contact as indicated in Figures 8 and 9, said inner edges at the center being provided with complementary clamp members 13 having depending wings 14 adapted for contact when the

50 table top is in its horizontal or normal condition for engagement by a locking bolt 15 so as to secure the top in its proper or operative condition. Also the joint between the table top leaves or members is spanned

55 near its ends by clip plates 16 secured by screws 17 or like fastening means to the

under surface of the table top and serving to brace and strengthen the joint when the table is in use.

When the table top is folded as indicated 60 in Figures 8 and 9 the free edges thereof are engaged by holding clamp 18 secured in place by screws 19 or the equivalents thereof. Obviously the clamp represented by the members 13 must be released in order 65 to permit the folding of the table top, as also must the clip plates 16, it being sufficient with regard to the latter to remove one of the terminal screws and swing the clip around to a position within the contour of 70 the other leaf or top member.

Depending from the members of the table top are the skirt boards 20 and 21 of which the latter, arranged in spanning relation with the joint between the table top leaves or 75 members are of sectional construction with the elements thereof connected by joint spanning clips 22. Within the skirting thus formed are arranged the legs having stationary stub members 23 and foldable members 24 hinged as at 25 to the stub members, and transversely connecting the legs in the planes of folding movement thereof, as a means of strengthening and fortifying 80 the construction when set up, are the braces 26 having members connected by hinges 27, with one of the members hinged as at 28 to one of the folding leg members as shown clearly in Figure 5. These braces may be 85 broken at the joint represented by the hinge 27 and the members thereof may be folded upon each other and in parallelism with the leg to which one of the members is hinged, so that said leg with the attached brace members can be folded into the housed position 90 clearly indicated in Figure 9 and thereby protected from scratching or injury by contact with adjacent objects in transportation or storage of the device.

Secured to the upper surface of the main 100 table top in spanning relation with the joint between the members thereof is a socket member 29 (which obviously must be removed in order to permit of the folding of the table top) and mounted in said socket 105 member is a spindle 30 depending from a serving table top 31 which is also constructed of foldable sections or members connected by a central hinge 32 and when in the normal or flat condition by transverse joint 110 spanning clip plates 33 similar to those used in connection with the main table top.

When folded the sections or members of the serving table top are secured by means of the clip 34 similar to the clip 18 used in connection with the main table top.

5 Also mounted upon and carried by the serving table top in spanning relation between the joint and the members thereof is a central pedestal 35 suitable for supporting a vase or centerpiece.

10 It will also be obvious from the foregoing description that whereas the joints between the folded and connected members of the structure are such as to permit of the arrangement of the device in a compact form

15 for storage or shipment under such conditions as to protect the highly finished or varnished surface which in the use of the device are exposed to view, the elements which are thus foldably connected are adapt-

20 ed to be rigidly secured in their operative positions when the table is set up, so that the necessary stability and strength are afforded to enable the structure to properly perform its functions.

25 Having described the invention, what is claimed as new and useful is:—

1. A table having its top composed of hingedly connected leaves or sections adapted to be folded with the upper surfaces 30 thereof in substantial contact, clamp members secured to the under surface of the top adjacent to the joint and provided with depending ears engaged by a clamp bolt, hingedly mounted leg members connected with the under side of the table top for movement 35 into position in substantial parallelism therewith, and braces arranged in the planes of

folding movement of said leg members and hingedly carried by one of each pair of said members for terminal contact with the other of said pair, the braces consisting of hingedly connected sections, a single hinge being arranged at the center of the joint between said table top members, and a serving table having a socket member disposed in housing relation with said hinge and in spanning relation with the joint between the first-named table top members and resting upon the surface of the latter.

2. A table having its top composed of hingedly connected leaves or sections adapted to be folded with the upper surfaces thereof in substantial contact, clamp members secured to the under surface of the top adjacent to the joint and provided with depending ears engaged by a clamp bolt, hingedly mounted leg members connected with the under side of the table top for movement into position in substantial parallelism therewith, and braces arranged in the planes of folding movement of said leg members and hingedly carried by one of each pair of said members for terminal contact with the other of said pair, the braces consisting of hingedly connected sections, and a serving table having foldably connected leaves or members and provided with a depending spindle, and a socket member supported by and in spanning relation with the joint between the members of the main table top for the reception of said spindle.

In testimony whereof he affixes his signature.

MOSE FISHER.
